(57) **CLAIM**

I claim the ornamental design for a tin and lid combination, as shown and described.

DESCRIPTION

FIG. 1 is a perspective view of a tin and lid combination showing my new design;

FIG. 2 is an exploded perspective view thereof;

FIG. 3 is a top plan view of FIG. 1;

FIG. 4 is a front elevational view, shown without the lid, the rear elevational view being identical thereto;

FIG. 5 is a side elevational view, the opposite side elevational view being identical thereto;

FIG. 6 is a top plan view of the lid;

FIG. 7 is a front elevational view of FIG. 6, the rear elevational view being identical thereto; and,

FIG. 8 is a side elevational view of FIG. 6, the opposite side elevational view being identical thereto.
